UNITED STATES PATENT OFFICE.

HENRY S. HALE AND JOHN B. KILBURN, OF PHILADELPHIA, PENNSYLVANIA, ASSIGNEES
TO THE HALE AND KILBURN MANUFACTURING COMPANY, OF PHILADELPHIA, PENN-
SYLVANIA, A CORPORATION OF PENNSYLVANIA.

SEAT.

No. 895,453.

Specification of Letters Patent.

Patented Aug. 11, 1908.

Application filed September 19, 1906. Serial No. 335,321.

To all whom it may concern:

Be it known that we, HENRY S. HALE and JOHN B. KILBURN, both citizens of the United States, and both residing at Philadelphia, in the county of Philadelphia and State of Pennsylvania, have invented a certain new and useful Improvement in Seats, of which the following is a specification.

The object of the present invention is to provide a chair or seat in which provision is made for the shift or adjustment of the back by the occupant, without rising from the seat.

A further object is to accomplish this in a chair of the revoluble type now commonly employed in Pullman cars.

A further object is to provide mechanism whereby the turning of the seat upon its support shall depend upon the position of the back, the purpose here being to permit the chair to be placed in a car near the side-wall thereof but at the same time guard against impact of the back with such wall in turning the seat to a new facing direction.

Other objects will be made apparent during the following description of a preferred form of the invention.

Figure 1 is a side elevation of a seat of the Pullman type, equipped with the invention; Fig. 2 is a section thereof on the line 2—2 Fig. 3; Fig. 3 is a plan view of certain metallic parts, the seat back and cushion being removed; Fig. 4 is an enlarged detail view, illustrating one of the several positions of the parts whereby the inclination of the back is effected; and Fig. 5 is an enlarged detail view on the line 5—5 Fig. 3.

In that form of the invention which we have selected for the present disclosure, we employ a pedestal base A, adapted to receive the spindle B carrying the supporting spider b having outwardly extending arms b', b'', b''' and b''. Said spider-arms are here shown as supporting a rectangular seat-frame C, comprising end members c, c', connected by the cross-members c'', c''''. Said frame may, if desired, be of wood, in which event said four members may be properly joined, or it may be of pressed steel, in which event it may be made integral. In either case, such frame is rigidly secured to the spider-arms by bolts or other suitable means.

D, D, designate guide-plates, one at either side of the seat-frame and here shown as

mounted in the end members c, c' thereof, 55 although if desired they may be supported from the spider-arms b', b''. Each of said guide-plates is provided with two connected guide-grooves or guideways d, d', here shown as bounded by inwardly projecting ribs, 60 although if desired said grooves may be stamped in the metal, in which event such ribs may be dispensed with. As best seen in Figs. 2 and 4, the guide-grooves d are approximately arc-shaped, while the guide-grooves d' are approximately straight, the same extending outward and rearward from the lowermost points of said guide-grooves d.

E, E, designate back-supporting arms or brackets having angular upward extensions 70 e upon which the seat-back E' is detachably secured. Each of said brackets is provided at its forward and rearward corners with studs or sheaves e', e'', of such size as to snugly fit within the guide-ways d, d'. In 75 the present embodiment of the invention, said studs or sheaves e', e'', bear such relation to each other with reference to the size and shape of the guideways d, d', that when the rearward studs or sheaves, e'', coact 80 with the ends of the guideways d', the forward studs or sheaves, e', will coact with the guideways d, the parts when in this position resulting in the normal (upright) position of the back shown in Fig. 2. In order 85 to adjust the back to the rearward inclination shown in Fig. 1, said studs or sheaves are caused, in the manner now to be described, to traverse said guideways d, d', whereby such adjustment is effected without materially changing the relation between the lower edge of the seat-back and the adjacent surface of the seat-cushion E'.

F designates a rock-shaft, here shown as mounted in bearings f, f, carried by the under 95 side of the seat-frame C. Preferably one end of said rock-shaft will project beyond said seat-frame and be provided at its end with an operating wheel f'' or handle f''. Said rock-shaft is provided with means ad- 100 jacent to each end for effecting the inclination of the back above referred to, and as the provision at one end for this purpose is the same as that at the other, we shall describe that at but one end only.

G designates a collar keyed or otherwise secured upon said shaft and provided with a crank-arm g, pivoted to which is a connect-

ing arm g' , the opposite end whereof is secured by means of pivot-pin g^2 to the inner face of one of the back-supporting arms or brackets E. As will be seen, the movement of the rock-shaft F, due to the operation of the wheel f' or lever f^2 , will, through the connecting arm g' , cause the back-supporting brackets E to move within the guideways d, d' . One extreme of the movement is illustrated in Fig. 2, and the other in Fig. 4. Of course, the movement of the rock-shaft may be arrested at any intermediate point, leaving the back in any desired position between these two extremes. In moving from the position shown in Fig. 2 to that shown in Fig. 4, the studs or sheaves e', e^2 , are carried forward, the studs or sheaves e' riding to the extreme ends of the guideways d . By having such studs or sheaves snugly fit said guideways, disagreeable lost motion is prevented and the back is firmly and rigidly supported in either of its extreme positions, as well as in any intermediate position.

If the seat here shown and described were mounted close to the wall of a car, it might readily be revolved when the back occupies the normal (Fig. 2) position. Should such back be in reclining position, however, it would make contact with the side of the car or with the window therein. Instead, therefore, of sacrificing car space by mounting the seats a sufficient distance from the side of the car to permit such revolution, we provide means for precluding the revolution of the seat save when the back is in the upright or substantially upright position here referred to as the normal position, i. e., that shown in Fig. 2. This provision is as follows:—The pedestal A is provided with two stops h, h' . With these stops coacts a pawl H pivoted at h^2 to the body of the spider b. Said pawl has a projecting arm h^3 , whose forward end is pivoted to an ear h^4 depending from the eccentric strap h^5 coacting with the periphery of a cam h^6 keyed or otherwise secured upon the rock-shaft F.

The under side of the pawl H is cut away at h^7 , as shown in Figs. 3 and 5. The outer surface of the end of said pawl makes contact with the stop h when the seat is revolved upon the pivot b to sufficient extent and in the direction indicated by the arrow i. On turning the seat in the opposite direction (indicated by the arrow i'), however, and to sufficient extent, contact is made between the cut-away portion h^7 , that is the inner side of the end of the pawl and the stop h' .

On reference to Figs. 1 and 2, it will be seen that when the back is in the normal (up-right) position, the strap h^5 , ear h^4 and arm h^3 are depressed and the pawl H is held in such a position on its pivot that its end is above and out of the path of the stops h, h' . In this position of the parts, therefore, the seat may be revolved at will in a complete

circle. When, however, the crank-arm or handle f^2 or wheel f' is operated to move the back-supporting brackets forwardly and thereby to rearwardly incline the back E', this involving the rotation of the shaft F 70 and cam h^6 , strap h^5 , ear h^4 and arm h^3 are elevated, thus correspondingly depressing the end of pawl H, and thereby moving the latter into the path of the stops h, h' . When the pawl is in this position, the turning movement of the chair is limited by the engagement of pawl H with one or the other of the stops h, h' and the chair can only turn through an arc of a magnitude determined by the position of the two stops about the 80 pivot axis of the chair. These stops are so positioned that they arrest rotation of the chair in either direction at such a point that the back will not engage the window or wall at the side of the car. 85

Having now described our invention, what we claim as new therein and desire to secure by Letters Patent is as follows:—

1. In a seat, the combination of a pedestal, a frame mounted to rotate thereon, a plate 90 secured to each of the sides of said frame and having a groove therein provided with an integral lower wall extending throughout the length of the groove, one part of the groove being substantially horizontal and the other 95 part inclined to the horizontal, a back, back-supporting arms secured to the side edges thereof, two studs secured to the lower end of each of said arms and extending into the groove in one of said plates, said studs bearing on the lower walls of said grooves to support said back, links pivotally connected to said back-supporting arms and means for operating said links to carry one of the studs on each of said arms from one end to the 105 other of the inclined portion of the groove into which it extends, substantially as set forth. 100

2. In a seat, the combination of a pedestal, a frame mounted to rotate thereon, a plate 110 secured to each of the sides of said frame and having a groove therein provided with an integral lower wall extending throughout the length of the groove, one part of the groove being substantially horizontal and the other 115 part inclined to the horizontal, a back, back-supporting arms secured to the side edges thereof, two studs secured to the lower end of each of said arms and extending into the groove in one of said plates, said studs bearing on the lower walls of said grooves to support said back, a shaft journaled in said frame, cranks on said shaft, links pivotally connected to said cranks and said back-supporting arms and means for rotating said 125 shaft to carry one of the studs on each of said arms from one end to the other of the inclined portion of the groove into which it extends, substantially as set forth. 120

3. In a seat, the combination of a rotata- 130

ble frame, a back mounted thereon, means for moving the back to various positions of adjustment, and means operated in adjusting said back for permitting free rotation of 5 said frame in either direction when said back is in one position of adjustment and for precluding more than a predetermined amount of rotational movement of the frame when the back is in another position of adjustment, 10 substantially as set forth.

4. In a seat, the combination of a rotatable frame, an adjustable back, manually operated means for effecting the adjustment of said back, and mechanism operated thereby 15 for permitting rotational movement of said frame through a predetermined range but precluding movement thereof beyond said range under certain conditions, substantially as set forth.

20 5. In a seat, the combination of a rotatable frame, an adjustable back movable to forward and rearward inclinations, means for effecting adjustment of said back to such inclinations, and mechanism operated thereby 25 for permitting rotational movement of said frame through a predetermined range but precluding movement thereof beyond said range when said back is at rearward adjustment, substantially as set forth.

30 6. In a seat, the combination with a support and a frame pivotally mounted therein, of an adjustable, non-reversible back, guideways carried by said frame, back-supports 35 having studs or sheaves coacting with said guideways, a rock-shaft and means for manually operating the same, a stop device intermediate of said frame and support, and interdependent connections between said rock-shaft and said stop device and between said 40 rock-shaft and back-supports, substantially as set forth.

7. In a seat, the combination of a support, a frame pivotally mounted thereon, a stop device between said frame and support in-

cluding a pawl adapted to co-act with stops 45 upon said support to permit rotation of said frame through a predetermined range, but preclude such movement thereof beyond said range, an adjustable back mounted on said pivoted frame, a rock shaft, and means 50 carried thereby for adjusting said back and for throwing said pawl to operative and inoperative positions, substantially as set forth.

8. In a seat, the combination of a support provided with stops, a frame pivotally 55 mounted on said support, a pawl adapted to co-act with said stops, an adjustable back, and mechanism for interdependently effecting the adjustment of said back and the operation of said pawl to permit rotational 60 movement of said frame upon said support through a definite range but preclude such movement beyond said range, substantially as set forth.

9. In a seat, the combination of a pedestal, 65 a frame mounted for rotation thereon, a back pivoted on said frame, a shaft extending across said frame and journaled in bearings thereon, connections between said shaft and said back, means for rotating said shaft and 70 thereby varying the inclination of the back, and means operated by the rotation of said shaft for permitting free rotational movement of the frame upon the pedestal or for permitting rotational movement of the frame 75 upon the pedestal through a definite range but precluding such movement beyond said range, substantially as set forth.

This specification signed and witnessed this 10th day of February, 1906.
